to Ames Company, Inc., Elkhart, Ind., a cor-
poration of Indiana

Application March 10, 1944, Serial No. 112,840

Term of patent 14 years

(Cl. D58—13)

To all whom it may concern:

Be it known that we, Howard F. Christner,
Frederick A. Lobley, and Charles Foster Miles,
citizens of the United States, residing at Elkhart,
in the county of Elkhart and State of Indiana,
have invented a new, original, and ornamental
Design for Container for Holding Medical In-
gredients and Implements of which the following
is a specification, reference being had to the ac-
companying drawing, forming a part thereof.

In the drawing:

Figure 1 is a front elevational view of a con-
tainer for holding medical ingredients and imple-
ments showing our new design;

Figure 2 is a side elevational view of the con-
tainer of Figure 1;

Figure 3 is a plan view of the lower section of
the container of Figure 1; and

Figure 4 is a perspective view looking at the
front of the container of Figure 1 with the cover
in disassembled and spaced relation with respect
to the body of the container showing the interior
of the latter.

We claim:

The ornamental design for a container for
holding medical ingredients and implements, sub-
stantially as shown.
